A. R. ENTRIKIN ET AL

BEACH CAPE

Filed March 29, 1920

UNITED STATES PATENT OFFICE.

ARTHUR R. ENTRIKIN AND LUCILE PALMER ENTRIKIN, OF OCEAN PARK,
CALIFORNIA.

BEACH CAPE.

Application filed March 29, 1920. Serial No. 369,807.

To all whom it may concern:

Be it known that we, ARTHUR R. ENTRIKIN and LUCILE PALMER ENTRIKIN, both citizens of the United States, residing at 5 Ocean Park, in the county of Los Angeles and State of California, have invented a new and useful Beach Cape, of which the following is a specification.

This invention relates to a garment to be 10 worn by persons clothed in bathing suits at beaches. Heretofore promiscuous kinds of garments for this purpose have been used, ranging from cumbersome bathrobes to an inadequately short sweater. At 15 many beaches very strict regulations are made with regard to such coverings, requiring the bather to cover the bathing suit with an outer garment when walking upon the walks or through the streets. 20 The various garments heretofore used to comply with such regulations have been subject to various objections amongst which may be mentioned absorption of water from the wet bathing suit causing chilling of the 25 person, and clinging of the outer garment to the form; difficulty of putting on and off the outer garment in case sleeves are used; and difficulty of handling the garment while on in case sleeves are not used; 30 clogging the meshes of the garment with sand while the bather lies upon the beach to sun himself; likelihood of fading the garment or trimmings thereof; rapid radiation of heat when the garment is wet and 35 the wearer stands in the cool breeze; rapid absorption of heat from sunshine; thus making the dry garment hot to the person in the sun. Another difficulty with the 40 garments heretofore used for such coverings is their liability of become rumpled and disheveled and soiled.

An object of this invention is to provide an outer garment for bathers which will be a light, strong, durable, attractive, and 45 comfortable garment; easy to don and remove; and easy to be fastened by oneself upon his own person; which garment will give freedom to the arms and hands of the wearer and allow the hands to be disposed 50 inside or outside the garment as may be desirable, to allow the hands to be free to fasten the garment on and to unfasten it from the person; and to afford comfortable and convenient pockets for holding articles 55 and for accommodating and protecting the

hands when the bather is walking, sitting, standing or lying down.

A further object is to provide a garment adapted to the above uses which is comparatively cheap and can be made of novel and striking appearance with a minimum amount of material; to avoid waste of material and to minimize the amount of labor required for making the garment.

We have discovered that the foregoing objects can be accomplished with the use of a material not heretofore known as being suitable or desirable for garments of this character.

We have discovered that by making a bathing cape of awning canvas we are enabled to provide a beach garment that is more satisfactory for the use of ocean bathers, than has heretofore been possible to provide. The material we thus employ is preferably eight ounce awning-canvas. Such canvas usually comes in stripes, and an object of this invention is to utilize such striped material in a way that will be attractive. We do not limit ourselves, however, to the use of striped canvas for this purpose.

An object is to provide a beach cape which is practically waterproof, wind proof, sand proof and sun proof; which will not cling to the form and hamper the walk like bath-robies; which is durable, lasting and washable; which very seldom requires laundering; is very light in weight; folds compactly; is easily carried in a suit case; and which, normally is light, weighing about 2 lbs.

An object is to provide a beach cape which has a breezy out of door appearance suggestive of coolness, and is comfortable and appropriate looking in the summer time compared with hot bath-robies; to provide a garment adapted to a style that is becoming to every figure. Also to provide a garment having novel pockets.

This novel beach covering is in the form of a cape and is easily slipped on, and avoids uncomforatableness of putting arms through wet sleeves.

Other objects, advantages and features of the invention may appear from the accompanying drawing, the subjoined detail description and the appended claims.

The accompanying drawing illustrates the invention.

Figure 1 is a front view of the garment in use.

Fig. 2 is a back view of the garment removed.

5 Fig. 3 is a fragmental view of the garment removed and thrown open to expose parts of the inside of the cape.

Fig. 4 is a section on line x^4 , Fig. 3 at the arm slit and pocket.

10 Fig. 5 is a fragmental section on line x^5 , Fig. 3, showing the construction of the collar, yoke and skirt.

Fig. 6 is a detail of the collar, yoke, one half of the skirt and one pocket piece.

15 Fig. 7 is a detail of the garment fastener.

Fig. 8 is a section of the same on line x^8 , Fig. 7.

The body 1 of the garment is formed of a rectangular piece of awning canvas 2, one-half of which piece is shown in Fig. 6. Said piece 2 is gathered at the top as indicated at 3 and is joined by stitches 4 to the yoke 5 some distance above the lower edge of the yoke. A collar 6 is joined to the neck hole 7 of the yoke and is thereby adapted to be worn either up or down.

The front edges and the bottom of the body 1 are folded over and hemmed as indicated at 8 and 9. The front edges of the 30 garment are straight from bottom to top and are provided with braid laces 10.

The laces 10 are hand dyed on braid and are secured to the yoke and body of the garment at the front edges thereof by grommets formed of two annular plates 11, 12, the latter being provided with an annular rivet 13 passed through the material of the garment and through the braid and riveted in a well known manner. This fastens the lace 35 in place and also forms an eyelet through which the lace may be passed for greater security to the garment.

Before the grommet is placed, one end of the tape is turned under the edge of the canvas and may be held by the grommet, by a seam, or by both.

The laces are thus secured in pairs to opposite edges of the garment and preferably are disposed with one pair at the neck hole, 50 another pair at the edge of the yoke and the third pair at about the waist line.

The seam at 4 where the skirt or body 1 is secured to the yoke is at the distance of, say an inch or an inch and a half above the 55 lower edge of the yoke so that the yoke gives a simulated yoke effect to the garment and the collar 6 is of sufficient width to practically extend from the neck hole 7 to the seam at 4 so that directly over the shoulders 60 there is a double thickness of material to shed rain.

14 indicates slits that are arranged at an angle of about 45 degrees to the edges of the body 1 at about the level of the waist line 65 and that extend toward the front edges of

the garment from a point about vertically below the tip of the shoulder of the wearer. Said slits are adapted to allow the hands of the wearer to be extended from the inside to the outside of the garment for the purpose 70 of fastening and unfastening the braid, and for any other purpose requiring the use of the hands outside of the garment.

Triangular pocket pieces 15 of the awning canvas are provided; the same being preferably equilateral triangles; each set with one side 16 being parallel to the appropriate hand slit 14 and the other side 17 being parallel to the edge of the garment.

The edge 16 is free and the other two 80 edges 17 and 18 are joined to the skirt by suitable means as the stitches 19. In this way the pockets are made and attached economically. They are arranged below the waist line and centrally so that the hands of 85 the wearer of the garment when extended through the slits 14 may readily enter the pockets.

It is thus seen that this novel cape is formed of only five pieces of awning canvas 90 and six laces or ties, three on each of the front edges at the upper portion of the cape; that the collar and yoke afford two thicknesses only over the shoulders and yet the cape has the appearance of having a shoulder 95 cape as well as a collar, the yoke thus giving a shoulder-cape effect and the collar being adapted to be worn either up or down and yet allow the garment to be light upon the shoulders of the wearer. 100

The collar and strings serve to hold the skirt in position with the slits and pockets just below the waist line in an appropriate position on the wearer to comfortably accommodate the hands when thrust through 105 the slits and into the pockets.

The oblique slits arranged about the level of the waist-line of the garment allow the hands of the wearer to be easily passed through from the inside out to handle the laces or ties in fastening the garment on the form. By constructing the pockets of 110 triangular pieces of awning canvas fastened to the outside of the garment with the upper edge free and in parallelism with the slit, the hands pass readily into the pockets with the arms in convenient position. 115

By making the cape of awning canvas it is practically insured against fading for the reason that awning canvas is particularly 120 dyed to retain its color in sun and rain.

Said awning canvas is made of hard twisted cotton and resists penetration of both moisture, heat and rain.

The awning canvas comes in such widths 125 as to readily cut to accommodate the purposes herein outlined with the stripes running up and down as shown in Fig. 1 of the drawing, and by cutting the triangular pieces as shown with the upper edges thereof 130

parallel to the slits, the stripes on said pockets give a distinctive ornamental effect to the front of the garment.

I claim:

- 5 1. A beach cape comprising a body formed of a piece of awning canvas; a yoke provided with a neck hole and joined to said body, and a collar joined to the neck hole of the yoke and adapted to over-lap the upper portion of the yoke; said yoke being joined to the body by a seam at some distance above the lower edge of the yoke and some distance below the lower edge of the collar so as to give the appearance of a shoulder.
- 10 15 2. A beach cape provided in front with slits at about the waist-line of the cape, and arranged aslant; and pockets having their mouths on the outside of the cape, said mouths arranged in parallelism with said slits and being adapted to accommodate the hands of the wearer when the same are passed through said slits.

3. A beach cape provided in front with 25 slits at about the waist-line of the cape, and arranged aslant upward toward each other; and pockets having their mouths aslant on the outside of the cape and arranged in parallelism with said slits and being adapted 30 to accommodate the hands of the wearer when the same are passed through said slits.

4. A beach cape having a body provided with two oblique slits to allow the hands of the wearer to be passed through the front 35 of the body; and two triangular pieces of material each having one edge arranged in parallelism with and adjacent to the slits respectively and having the other edges joined to the garment to form a pocket 40 having its mouth adjacent to the slit.

In testimony whereof, we have hereunto set our hands at Ocean Park, California, this 22nd day of March, 1920.

ARTHUR R. ENTRIKIN.

LUCILE PALMER ENTRIKIN.

Witness:

JANE M. AKINS.
